(57) **CLAIM**

We claim the ornamental design for a table saw base and panels, as shown and described.

DESCRIPTION

FIG. 1 is an elevational view of a table saw base according to our new design, as viewed from the front left corner of the table saw, the broken lines of the table saw base are for illustrative purposes only and form no part of the claimed design;

FIG. 2 is an elevational view of the table saw base of FIG. 1, as viewed from the front right corner of the table saw; FIG. 3 is an elevational view of the table saw base of FIG. 1, as viewed from the rear right corner of the table saw; FIG. 4 is an elevational view of the table saw base of FIG. 1, as viewed from the rear left corner of the table saw;

FIG. 5 is a perspective view of an alternate embodiment of the table saw base of FIG. 1, as viewed from the front left corner of the table saw, the broken lines of the table saw base are for illustrative purposes only and form no part of the claimed design;

FIG. 6 is a perspective view of the table saw base of FIG. 5, as viewed from the front right corner of the table saw;

FIG. 7 is a perspective view of the table saw base of FIG. 5, as viewed from the rear right corner of the table saw; and, FIG. 8 is a perspective view of the table saw base of FIG. 5, as viewed from the rear left corner of the table saw.
